UNITED STATES PATENT OFFICE.

THOMAS J. GORDON, OF EUREKA SPRINGS, ARKANSAS, ASSIGNOR, BY DIRECT AND MESNE ASSIGNMENTS, OF TWO-THIRDS TO ROBERT L. MEADOR, OF SAME PLACE, AND GEORGE W. FINN, OF MUNDELL, ARKANSAS.

FIRE AND BURGLAR ALARM.

SPECIFICATION forming part of Letters Patent No. 469,648, dated February 28, 1892.

Application filed September 4, 1891. Serial No. 404,770. (No model.)

To all whom it may concern:

Be it known that I, THOMAS J. GORDON, a citizen of the United States, and a resident of Eureka Springs, in the county of Carroll and 5 State of Arkansas, have invented certain new and useful Improvements in Fire and Burglar Alarms; and I do declare the following to be a full, clear, and exact description of the invention, such as will enable others skilled in 10 the art to which it appertains to make and use the same, reference being had to the accompanying drawings, and to letters of reference marked thereon, which form a part of this specification.

15 Figure 1 of the drawings is a representation of the alarm and is a diagrammatic view. Fig. 2 is a perspective view of the connecting mechanism over the door. Fig. 3 is a detail view, enlarged, of same. Fig. 4 is a view of 20 the mechanism as arranged on windows. Fig. 5 is a face view of the alarm. Fig. 6 is a detail view of one of the connecting-levers.

25 This invention has relation to certain new and useful improvements in burglar and fire alarms; and it consists in the novel construction and combination of parts, as hereinafter described, and pointed out in the claims.

In the accompanying drawings, illustrating the invention, the letter A designates the interior of a room or building, to which my invention is shown as applied.

30 In putting my alarm into operation I first take a spring, such as that shown at B, and secure it to the wall of a room or building at one end thereof and near the ceiling. This spring may consist of a piece of wire bent to 35 form an eye or coil, having the diverging arms a a'. On the end of the arm a is an eye a', to which I secure one end of a cord or 40 wire C, which runs the length of the room or building to the opposite end or to wherever desired, and is connected to an eye or screw b, said cord running over anti-friction pulleys wherever necessary. The spring B is arranged 45 so that its tension will normally hold the cord or wire C taut.

Over each door or window I provide an arc-shaped lever D, pivotally secured at its center and having one of its arms d provided

with an eye, through which is passed the wire 50 or cord C.

To each window-casing, just above the upper edge of the lower sash, is secured a small arm or lever E, pivoted at its center. One arm e of this lever is adapted to be turned 55 into position to be engaged by said sash when raised and the other end or arm e' is provided with a small hook, which, when the alarm is set, engages an eye f on a wire or cord F, which at its upper end is connected to the 60 opposite arm of the lever D. It will therefore be seen that when any window is raised the cord F will be pulled downwardly, slackening the tension of cord C. When the alarm is not set, the hook and eye are disconnected. 65 Connection may be made with both sashes, if desired.

For each door I secure to the casing by a central pivot an angle iron or lever G, to one arm of which is fastened a cord H, connected 70 to one arm of the angle-lever D. The other arm is adapted to be turned down when the alarm is set in front of the door. When the door is opened, said arm will be engaged thereby and the cord H pulled, causing the 75 slackening of the wire or cord C. When not in use, the angle irons or levers may be turned up out of the way. In connection with these levers G, I may employ two small angle-springs G', which, when the door is opened, will hold 80 said levers back, and which will hold them again in operative position when the door is closed. These two springs are secured to the casing just under the lever G—one on each side of the lower arm thereof. The shorter 85 arms of said springs extend toward each other and come nearly together at their free ends. When the door is opened, it will engage said arm of the lever, forcing it through between the ends of the springs and holding it there 90 until the door is closed, when it will be again pushed back inside of said springs.

I will now describe the alarm, which is located at any desired point in the building. Inclosed in a suitable box or case is a spring 95 and pinion-gear K with winding mechanism k, similar to that employed in clock-work, provided with an escapement J, to which is con-

nected a bell-hammer, which under the movement of said escapement sounds a bell L. M is a bail-lever device pivoted within said casting and having an arm m, which projects 5 therethrough and is connected with a cord or wire N to the main wire C. At the opposite end of this bail device is an arm n, which, when the arm m is pressed or held forward, engages the stem of the bell-hammer, throwing 10 the escapement out of gear and preventing the sounding of the alarm, said stem in such position being held between the arm n and the post P. The tension of the wire or cord C is sufficient to normally hold this lever 15 forward and prevent the alarm from sounding. When, however, a sash is raised or a door opened and the tension relaxed, a spring presses against said bail device, throwing it backwardly, and the alarm is sounded. It 20 will be seen, moreover, that if a fire breaks out in the building, as soon as the flames reach the cord between the attaching-spring B and the alarm, said cord, if of inflammable material, will be burned in two, thus releasing the 25 tension and sounding the alarm. A connection R may also be made between the door-bell knob at the door and said alarm to be used as an ordinary door-bell. It may also be connected with and operated by push-but- 30 tons. These alarms may be conveniently carried and put up temporarily by traveling men or others stopping at hotels or boarding-houses, requiring but a few screws and a few moments' time.

35 The cords C, F, and R may be made of any

color to match the color of the wall or the paper thereon, thereby rendering it less conspicuous, or where put up permanently may be entirely concealed.

Having described this invention, what I 40 claim as new, and desire to secure by Letters Patent, is—

1. In an alarm device, the combination, with the alarm and the tension-cord connected thereto, of the mechanism operated by the 45 opening of a door for slackening said cord, and mechanism comprising a lever D, having a connection with the tension-cord, the pivoted angle iron or lever G, secured to the door-casing and having one of its arms flexibly connected with an arm of the lever D and the other arm arranged to be engaged by the opening of the door, and the device for holding 50 said lever G, substantially as specified.

2. In an alarm device, the combination, 55 with the alarm and the tension-cord, of a lever G, pivotally secured to the casing of each door and having a flexible connection with said cord, said lever having an arm arranged to be engaged by the door when opened, and 60 the angle-springs G', secured to the casing and operating, as described, to hold said lever in position, substantially as specified.

In testimony whereof I affix my signature in presence of two witnesses.

THOMAS J. GORDON.
